PACKAGING CONTAINER FOR FOOD PRODUCTS

Sam A. Mazzola, 1852 Rural St., Rockford, Ill. 61107,
and William J. Duncan, Jr., R.R. 2, Bemes Road, Crete,
Ill. 60417

Filed Mar. 31, 1972, Ser. No. 240,329

Term of patent 14 years

Int. Cl. D9—03

U.S. Cl. D9—219

FIG. 1

FIG. 2

FIG. 3

FIG. 1 is a top plan view of a packaging container for food products in an open position showing our new design;

FIG. 2 is a side elevational view thereof; and
FIG. 3 is an isometric view with the lid partly closed.

The top of the lid is plain and unornamented.

We claim:

The ornamental design for a packaging container for food products, as shown and described.
